CLAIM

An ornamental design for a plating machine for depositing precious metals onto discrete components, as shown and described.

DESCRIPTION

FIG. 1 is a front elevational view of a plating machine for depositing precious metals onto discrete components showing my new design;

FIG. 2 is a left side elevational view thereof;

FIG. 3 is a top plan view thereof;

FIG. 4 is a right side elevational view thereof; and

FIG. 5 is a perspective view thereof.

The back of the machine is plain and unornamented.
